UNITED STATES PATENT OFFICE

162,560

TOY AIRPLANE

Clyde L. Miller, Berkley, and Robert D. Brandon,
 Detroit, Mich., assignors of one-third to J.
 Harold Steffes, Berkley, Mich.

Application March 23, 1950, Serial No. 8,712

Term of patent 14 years

(Cl. D34—15)

To all whom it may concern:

Be it known that Clyde L. Miller, a citizen of the United States of America, residing in Berkley, in the county of Oakland and State of Michigan, and Robert D. Brandon, a citizen of the United States of America, residing in Detroit, in the county of Wayne and State of Michigan, have invented a new, original, and ornamental Design for a Toy Airplane, of which the following is a specification, reference being had to the accompanying drawing, forming a part thereof.

Fig. 1 is a top plan view of a toy airplane, showing our new design;

Fig. 2 is a side elevation;

Fig. 3 is a front elevation;

Fig. 4 is a bottom view; and

Fig. 5 is a perspective view.

We claim:

The ornamental design for a toy airplane, as shown.

CLYDE L. MILLER.
 ROBERT D. BRANDON.
